TRIP CASING SPEAR

Application filed September 17, 1928, Serial No. 306,565, and in the Netherlands June 19, 1928.

This invention relates to trip casing spears as extensively used for extracting strings of pipes or casings sunk in deep wells. Such spears comprise a central wedge-shaped body 5 adapted to be coupled through a jar with a string of rods and coacting with slips in such a manner that said slips are radially forced outwards against the inner wall of the casing and grip the same when said body is hoisted. If it should be impossible by the application of repeated upward pulls and jerks to extract the string of casings, the slips should be released by a downward motion of the central body, whereupon the spear should be capable of being pulled out of the well without the slips reengaging and gripping the inner casing walls. To this end the central body is provided with a bottom extension encircled by a coiled spring bearing with its lower end against a collar on said extension and in contact with its upper end with an annulus releasably locked to the said extension. When the slips engage and grip the casing to be extracted, they serve as fixed 15 abutments which limit the extent of upward motion of the annulus, but on a strong upward pull being exerted on the wedge the annulus is tripped so as to have freedom of upward axial movement over the bottom extension under the influence of the coiled spring. Therefore, if the casing cannot be extracted and the wedge is lowered through a short distance, whereby the slips disengage the inner casing wall, the annulus pushes the slips upward relative to the wedge so as to keep them out of contact with the said wall when the spear is pulled out of the well. In these known devices, the slips, the wedge, the spring loaded annulus and the trip require a very exact relative setting in order that the slips may cause the annulus to be tripped in the moment wherein they have gripped the casing with just sufficient force not to be raised under the influence of the spring. This relative setting of the operative parts can, however, be effective only when the casing to be extracted has throughout the exact inner diameter for which the spear has been designed, but unfortunately 20 this diameter may vary considerably owing to

certain tolerances to which manufacturers are working and also to the fact that casings of the same size are made in various weights, which entails various diameters.

Now, the object of the present invention is 55 a trip casing spear, the operation of which is not interfered with by the normal variations in the inner diameter of the pipes, so that the annulus is always tripped with certainty.

In accordance with the invention, the casing spear is provided with a central bar adapted to be pushed downward either under the action of the jar, or through a yoke coacting with an auxiliary pipe sunk into the casing, or through a weight, or in another manner, whereby it forces the annulus down through the medium of a cross bar or a bridge-piece, so that the annulus is tripped. In this manner, the tripping is rendered independent of the operation of the slips. It will be understood that the novel tripping device may be combined with the conventional construction outlined above.

The annexed drawing illustrates, by way of example, but not of limitation, three different embodiments of the invention. On this drawing:

Fig. 1 is a longitudinal sectional elevation of a complete trip casing spear in a position 80 wherein the slips have firmly gripped the casing but wherein the trip has not yet been pulled out of its hole.

Fig. 2 is a longitudinal sectional elevation of part of another device, in which the tripping is effected through an auxiliary pipe sunk into the casing.

Fig. 3 is a longitudinal sectional elevation of part of still another embodiment, in which the tripping is brought about by a weight 85 adapted to be lowered within an auxiliary pipe.

Fig. 4 is a longitudinal sectional elevation of the tripping device, on an enlarged scale.

Fig. 5 is a cross sectional plan view along 90 the line V—V in Fig. 1.

Sunk into the casing 8 to be extracted is a central wedge-shaped body 10, the top part 11 of which is coupled with a jar 9 suspended from a string of rods not shown. Said wedge 100

10 has a cylindrical bottom extension 12 and cooperates with the usual slips 13. Associated with the bottom extension 12 through a trip 15 is the annulus 14 which is loaded by a coiled releasing spring 17 bearing against a nut 18 screwed upon the lower end of said extension 12. The trip 15 is loaded by a coiled locking spring 16 and located within a hole 26 of the annulus, said hole being closed by means of a screw 27.

The extension 12 is provided with a recess 19 for accommodating a cross bar or bridge piece 20, the ends of which extend into recesses 21 of the annulus 14, see Fig. 4.

Located within a central bore hole of jar 9 is a push bar 22. Another push bar 23, located in alignment therewith in a central bore hole of the wedge 10, 11, is supported with its lower end by the bridge piece 20 so that, when the movable part of the jar 9 is lowered, the bar 23 through the bridge piece 20 forces the annulus 14 down. It should be assumed that the wedge 10 has been firmly clamped between the slips 13 so that it can only be forced down by a heavy blow. The recess 19 has an axial length permitting the annulus 14 to move down through the required distance (Fig. 4), whereby the undercut head 24 of trip 15 disengages the inclined top wall of the recess in the bottom extension 12 so that spring 16 can push the trip outwards. Besides, said head 24 moves uphill over a sloping surface 25, whereby the trip is positively forced outwards, even if spring 16 should fail to do the work owing, for instance, to the presence of dirt.

If it is desired to also use the conventional device described in the preamble, the recess in the extension 12 for receiving the head 24 of the trip 15 may be made helicoidal, so that the axial position of the locked annulus 14 relative to the extension 12 can be varied.

According to Fig. 2, a yoke 29 has freedom of axial movement in a recess 30 of an intermediate part 28 between the jar 9 and the top portion 11 of the wedge 10. An auxiliary pipe 31 sunk into the casing 8 is adapted to exert pressure upon the yoke 29, which again transmits said pressure to bar 23.

The wedge 10 may so forcibly be clamped between the slips 13, that the jar 9 can be unscrewed and a pipe 32 (Fig. 3) provided at its lower end with a threaded socket 33 may be screwed to the top portion 11 of the wedge 10. The weight of this pipe 32 may be sufficient to disengage the wedge 10, otherwise a heavy blow on said pipe will have the desired effect, it being understood that a weight (not shown) lowered into said pipe 32 and exerting the required pressure upon the push bar 23 should previously trip the annulus 14.

Claims:

1. In a trip casing spear, the combination of a central wedge-shaped body, gripping slips adapted to be forced radially outwards

by upward movement of said body, an annulus adapted to exert upward pressure upon the slips and keep the same in inoperative position, a spring adapted to exert upward pressure upon the said annulus, means for locking said annulus against axial movement relative to said body, a central push bar adapted to exert downward pressure upon said annulus so as to displace it against the action of said spring and cause it to be tripped, and means operable from above whereby downward pressure can be exerted upon said bar.

2. In a trip casing spear, the combination of a central wedge-shaped body, gripping slips adapted to be forced radially outwards by upward movement of said body, an annulus adapted to exert upward pressure upon the slips and keep the same in inoperative position, a spring adapted to exert upward pressure upon the said annulus, a trip located within a hole of the annulus, a recess in said body for receiving a projection of said trip, a sloping surface forming a wall of said recess and adapted to positively push said trip out of said recess when the annulus is moved down relative to said body, a central push bar adapted to exert downward pressure upon said annulus so as to displace it against the action of said spring and cause it to be tripped, and means operable from above whereby downward pressure can be exerted upon said push bar.

3. In a trip casing spear, comprising a central wedge-shaped body, gripping slips cooperable therewith, an annulus adapted to exert upward pressure upon the slips to keep the same in inoperative position, means adapted to exert upward pressure upon said annulus; means for locking said annulus against axial movement relative to said body, and a separate, positive means for disengaging said locking means, whereby said annulus may exert upward pressure upon said slips.

4. In a trip casing spear, comprising a central wedge-shaped body, gripping slips cooperable therewith, an annulus adapted to exert upward pressure upon the slips to keep the same in inoperative position, means adapted to exert upward pressure upon said annulus; means for locking said annulus against axial movement relative to said body, and a separate, substantially centrally-located, positive means for disengaging said locking means, whereby said annulus may exert upward pressure upon said slips.

5. In a trip casing spear, comprising a central wedge-shaped body, gripping slips cooperable therewith, an annulus adapted to exert upward pressure upon the slips to keep the same in inoperative position, means adapted to exert upward pressure upon said annulus; a latch for locking said annulus against axial movement relative to said body,

and an axially-movable rod for disengaging said locking means, whereby said annulus may exert upward pressure upon said slips.

6. In a trip casing spear, comprising a central wedge-shaped body, gripping slips co-operable therewith, an annulus adapted to exert upward pressure upon the slips to keep the same in inoperative position, means adapted to exert upward pressure upon said annulus; said annulus having a recess extending inwardly from the outer periphery thereof, a latch in said recess for locking said annulus against axial movement, relative to said body, a member to which said latch may secure said annulus, resilient means adapted to urge said latch outwardly of said recess and away from the member to which it is latched, said latch normally being in its latched position, and an axially-movable, substantially centrally located rod for positively releasing said latch, whereby said annulus may exert upward pressure upon said slips.

7. In a trip casing spear, a central wedge-shaped body, having a downwardly-extending extension thereon, gripping slips co-operable with said body, an annulus arranged about said extension and adapted to exert upward pressure upon the slips, to keep the same in inoperative position; said annulus having a recess extending inwardly from the outer periphery thereof, a latch in said recess having a head on its inner end, resilient means adapted to urge said latch outwardly of said recess and away from the extension, said extension having a recess cooperating with said first-mentioned recess, and in which said head normally engages, said last-mentioned recess extending outwardly and downwardly at its lower extremity, and centrally located means positively actuating said annulus to force it downwardly whereby the latch may be released, at which time it may exert upward pressure upon the slips.

8. In testimony whereof I have signed my name to this specification.

GODEFRIDUS HENDRIKUS CLERKX van KEULEN.
